TOOTHBRUSH

James W. Moll, 1035 S. Clayton Way,
Denver, Colo. 80209

Filed May 12, 1966, Ser. No. 2,274

Term of patent 14 years

(Cl. D9—2)

FIG. 1

FIG. 2

FIG. 3

FIG. 4

FIGURE 1 is a perspective view of a toothbrush showing my new design;

FIGURE 2 is a top plan view;

FIGURE 3 is a side elevational view; and

FIGURE 4 is a cross-sectional view thereof, taken along the line 4—4 of FIGURE 3, shown partly in full and taken on an enlarged scale.

I claim:

The ornamental design for a toothbrush, as shown.
